Patented June 4, 1929.

UNITED STATES PATENT OFFICE.

EARL E. EICKMEYER, OF DAYTON, OHIO, ASSIGNOR, BY MESNE ASSIGNMENTS, TO WAYNE COMPANY, OF FORT WAYNE, INDIANA, A CORPORATION OF INDIANA.

LIQUID-DISPENSING APPARATUS.

Application filed March 14, 1925. Serial No. 15,471.

This invention relates to a liquid dispensing apparatus and more particularly to a gasoline dispensing apparatus comprising a transparent receptacle into which the gaso-
line is pumped and from which it is delivered through a hose to the gasoline tank of an automobile, such devices being in common use at filling stations.

It is desirable that a delivery receptacle of this character should be drained at night or when the attendant is absent for any considerable period of time. To accomplish this it is customary to provide the delivery receptacle with a drain pipe leading back to the storage tank and to control this drain pipe by a valve. This valve is so arranged as to be conveniently actuated by the operator and it affords an unscrupulous operator an opportunity to defraud the customer by diverting a part of the measured quantity of gasoline from the delivery receptacle to the storage tank.

One object of the present invention is to provide in an apparatus of this kind a delivery receptacle having means for draining the same which will be of such a character that no part of the liquid can be returned to the storage tank while the delivery receptacle is connected with the customer's gasoline tank; and to this end it is a further object of the invention to utilize the delivery hose as a part of the drain system.

A further object of the invention is to provide in connection with such an apparatus means for connecting the delivery hose with a drain pipe; and to control the flow of liquid from the hose to the drain pipe by a valve which will be automatically operated when the connection is made.

40 A further object of the invention is to provide means for automatically opening the valve which controls the flow of liquid through said hose, when the hose has been connected with the drain pipe.

45 Other objects of the invention will appear as the apparatus is described in detail.

In the accompanying drawings Fig. 1 is a side elevation of a gasoline pump, partly broken away to show my invention applied thereto; Fig. 2 is a front elevation of the connecting device for connecting the hose with the drain pipe; Fig. 3 is a longitudinal sectional view of the connecting device; Fig. 4 is a rear elevation of the connecting device; Fig. 5 is a section taken on the line 5-5 of

Fig. 3; Fig. 6 is a section taken on the line 6-6 of Fig. 3; Fig. 7 is a section taken on the line 7-7 of Fig. 5; and Fig. 8 is a section taken on the line 8-8 of Fig. 3.

In these drawings I have illustrated one embodiment of my invention and have shown the same as applied to a gasoline dispensing apparatus of a well known character but it will be understood that the invention may take various forms and may be used in connection with dispensing apparatus of various kinds.

In the present embodiment of the invention I have shown the same in connection with a gasoline dispensing apparatus of a well known type and which comprises a delivery receptacle, to receive the gasoline from the usual underground storage reservoir, and a hose leading from the delivery receptacle for conveying the gasoline to the tank of the automobile or other point of discharge, and having therein a valve to control the flow of gasoline through the same. The delivery receptacle is provided with a drain conduit leading back to the storage reservoir and, in the present instance, this conduit extends to near the top of the receptacle and constitutes an overflow pipe. To enable the delivery receptacle to be drained through the hose to the storage reservoir I have provided means for connecting the hose with the drain conduit. This connecting means may take various forms but preferably it consists of a nozzle on the end of the hose, a receptacle connected with the drain conduit and adapted to receive the nozzle and means for retaining the nozzle in the receptacle. In order that the valve in the hose may be automatically opened when the connection between the hose and drain conduit has been established I provide means controlled by some part of the connecting means for actuating that valve, thus insuring that when the hose is properly connected with the drain conduit the valve will be opened and the gasoline permitted to flow from the delivery receptacle through the hose and drain conduit to the storage reservoir. If desired, a valve may also be provided to control the connection between the drain receptacle and the drain conduit, this valve being also controlled by the means for connecting the hose with the conduit.

As here shown, the dispensing apparatus comprises a standard 1 mounted on a base 2

and having mounted on its upper end a transparent delivery receptacle 3. Arranged within the standard or casing 1 is a pump by means of which the gasoline, or other liquid, 5 is pumped from the storage tank into the delivery receptacle 3. The pumping mechanism forms no part of the present invention and as it is not necessary to an understanding of the invention I have not shown the 10 same in the drawings. Connected with the lower end of the delivery receptacle 3 is a delivery hose 4 by means of which the liquid is delivered to the gasoline tank of an automobile or to such other point of discharge as may 15 be desired. The hose 4 is here shown as the usual flexible tube but it will be obvious that any suitable conduit may be used for this purpose. This hose is provided with the usual nozzle 5 to facilitate the connection between 20 the same and the tank to which the liquid is to be delivered. The flow of liquid through the hose 4 is controlled by a valve 6 which is interposed between the same and the delivery receptacle and which is controlled by a handle 25 7. This handle is usually so arranged that the valve will be opened when the handle is moved upwardly and preferably the handle is weighted so that it will automatically close the valve when released. The delivery 30 receptacle is provided with an overflow pipe 8 which extends from a point near the top of the receptacle to the storage tank, for the purpose of returning to the storage tank any 35 excess liquid which may be pumped into the delivery receptacle. It will be understood that the outlet of the overflow pipe is so arranged that the storage receptacle when full will contain a certain measured amount of liquid. 40 In order that the contents of the delivery receptacle may be drained back into the storage tank through the delivery hose I have provided a connecting socket or drain receptacle adapted to receive the nozzle 5 and 45 which is provided with an outlet through which the liquid may escape from the hose to the storage tank or to such other receptacle as may be desired. This socket or drain receptacle may be of any suitable character 50 which will enable it to receive the end of a hose and will permit the liquid to flow from the hose to the tank or other receptacle. In the present device the hose is provided with a nozzle of a type adapted to enter the gasoline tank of an automobile and the drain receptacle is designed to cooperate with this nozzle. It will be obvious, however, that if the nozzle were omitted the end of the hose 55 itself could be inserted in a drain receptacle of suitable shape and would thus constitute in effect a nozzle. The outlet may be controlled by a valve and this valve may be automatically actuated, preferably by the insertion of the nozzle into the socket. I have 60 also provided means whereby the insertion 65 of the nozzle into the connecting socket will open the valve 6 in the hose line and thus cause the contents of the delivery receptacle to drain through the hose line, connecting socket and drain pipe to the storage tank. 70 The connecting and controlling device may take various forms and may be mounted in any suitable position with reference to the dispensing apparatus but I prefer that the connecting device should be mounted in the base 2 of the 75 standard or casing 1 and the present device has been designed with that end in view. As here shown, the connecting socket or drain receptacle is in the form of an elongated chamber 9, the outer end of which is open. This 80 drain receptacle is supported within the base 2 of the standard and the outer end of the same projects through an opening in the base, as shown in Fig. 1. The outer end of the drain receptacle is preferably provided with a 85 flange or connecting plate 10 which is secured to the outer side of the wall of the base and serves to support the drain receptacle in a position within the base. The nozzle 5 of the delivery hose is usually bent to facilitate its insertion into the gasoline tank and, in the present instance, the drain receptacle is given a somewhat similar shape. The drain receptacle is provided near its outer end with a seat 90 95 100 105 110 115 120 125 130 135 140 145 150 155 160 165 170 175 180 185 190 195 198 200 205 210 215 220 225 230 235 240 245 250 will press the retaining device and the flange on the nozzle inwardly and thus cause the shoulder to engage its seat firmly. It will be noted that the retaining device 15 is supported at its outer end on narrow lugs 17 which constitute in effect a pivotal support so that the upper end thereof is free to move toward and from the flange or plate 10, the points of contact between the arms 16 and the flange of the nozzle also being narrow, as shown at 18. The retaining device may be actuated in any suitable manner to move the same into and out of engagement with the flange 12 of the nozzle. As here shown, it is provided with a longitudinal slot 19 in which is arranged a disk 20. This disk is eccentrically mounted on a shaft 21 journaled in lugs 22 secured to the flange or plate 10 and has secured thereto an operating handle 23. The shaft 21 has a non-circular portion to receive the disk 20 and hold the latter against rotation with relation to the shaft. In the present arrangement the shaft extends through the side walls of the slot 19 in the retaining device 15, these walls being slotted, at 47, to permit the retaining device to have sliding movement with relation to the shaft. The relative positions of the disk and handle may be such that the retaining member will be moved into its operative position by the movement of the handle either in an upward direction or a downward direction. In the present instance, the arrangement is such that the upward movement of the handle will impart upward or operative movement to the retaining device and the handle is provided with an aperture 24 which, when the retaining device is in its operative position, will be in line with an apertured lug 25 so that the hasp of a padlock 26, or other suitable locking device, may be inserted through the two aligned apertures to lock the retaining device in its operative position.

In order to provide a tight joint between the shoulder 12 on the nozzle and its seat this seat is preferably formed of packing material, or other more or less yieldable substance, and inasmuch as such a material is subjected to wear and compression which might cause leakage I have mounted the seat on a sleeve 27 which is slidably mounted in the outer portion of the drain receptacle and is pressed outwardly by a spring 28 confined between a shoulder on the sleeve and a ledge 29 extending inwardly from the wall of the drain receptacle.

The drain receptacle or connecting socket 9 is provided with an outlet leading to the point of discharge and, as here shown, this outlet is in the form of a passageway 30 which is connected with a drain pipe. Preferably the passageway is connected with the overflow pipe 8 and to this end I have provided a substantially vertical passageway 31 with which the outlet 30 communicates and which is interposed in the overflow pipe, the lower portion of which thus constitutes the drain pipe. In the present device, the vertical conduit 31 is formed integral with the drain receptacle but obviously the outlet of the drain receptacle may be connected with the drain pipe in any suitable manner. The outlet 30 is controlled by a valve 32 which is here shown as a swinging gate valve and is supported by an arm 33 rigidly secured to a shaft 34 journaled in the walls of the drain receptacle and conduit 31. Rigidly secured to this shaft is a weighted arm 34^a so arranged that the weight on this arm will tend to move the valve to its closed position and retain it in that position. Rigidly secured to the shaft 34 and extending into the lower portion of the drain receptacle is a finger 35 which is so positioned that it will be engaged by the end of the nozzle 5 when the latter is inserted in the drain receptacle and will be actuated by that nozzle to rock the shaft 34 and move the valve 32 to its open position, thus automatically connecting the drain receptacle with the drain pipe. In the present construction the valve mechanism is arranged within a casing or chamber 36 which is formed integral with the drain receptacle 9 and which is provided with a closure 37 through which access may be had to the valve. Rigidly connected with the shaft 34 is a second arm 38 to which is connected the lower end of a rod 39 which extends upwardly through the standard or casing 1 and projects beyond the upper end thereof where it is provided with a hook shaped portion 40 which overhangs the finger 41 rigidly secured to the operating handle 7 for the valve 6; the arrangement being such that when the shaft 34 is actuated by the nozzle to open the outlet 30 the hook shaped end of the rod will engage the finger 41 to open the valve 6, thereby causing the delivery receptacle 3 to be placed in communication with the drain pipe, this being accomplished automatically by the insertion of the nozzle into the drain receptacle. The hook shaped end of the rod 39 is so arranged that when the valve 32 is in its closed position this hook shaped portion will lie above and out of contact with the finger 41 so that it will not in any way interfere with the normal operation of the hose valve.

The operation of the device will be readily understood from the foregoing description and it will be apparent that I have provided means for draining the delivery receptacle which is of such a character that it cannot be used to defraud the customer. The delivery receptacle can be drained only through the delivery hose and obviously when this delivery hose is connected with the customer's gasoline tank the liquid cannot be drained back into the storage tank. The connecting device between the hose and the drain pipe is of such a character that the insertion of the nozzle will automatically establish commun- 130

cation between the delivery receptacle and the drain pipe and when the nozzle is locked in position an absolutely tight joint will be provided which will effectually prevent the 5 escape of vapors. As soon as the nozzle is withdrawn the valves are automatically closed and are held in their closed positions, thus preventing any escape of gasoline vapors.

While I have shown and described one embodiment of my invention I wish it to be understood that I do not desire to be limited to the details thereof as various modifications may occur to a person skilled in the art.

Having now fully described my invention, 15 what I claim as new and desire to secure by Letters Patent, is:

1. In a device of the character described, a hose leading from a delivery receptacle, a nozzle carried by said hose and having a circumferential flange forming a shoulder thereon, a drain receptacle having means to connect the same with a storage reservoir, adapted to receive said nozzle and having a seat to engage said shoulder, a supporting plate secured to said drain receptacle, a retaining device having a bifurcated end portion, the arms of which are movable into and of engagement with said flange on the opposite sides of the hose, means for movably mounting said retaining device on said supporting plate, and means for moving the bifurcated end portion thereof into contact with said flange and then forcing said portion of said retaining device inwardly to press the shoulder of said flange against said seat.

2. In a device of the character described, a hose leading from a delivery receptacle, a nozzle carried by said hose and having a circumferential flange forming a shoulder thereon, a drain receptacle having means to connect the same with a storage reservoir, adapted to receive said nozzle and having a seat to engage said shoulder, a supporting plate secured to said drain receptacle, a retaining member having a bifurcated end portion, the arms of which are movable into and out of engagement with said flange on the opposite sides of the hose, said member being slidably supported on said supporting plate and having the arms of its bifurcated end tapered and movable toward and from said supporting plate, and also having a slot formed therein, a shaft, a disk eccentrically mounted on said shaft and arranged in said slot, a handle connected with said shaft for actuating said disk, and a fixed part carried by said supporting plate and arranged to engage the tapered arms of said retaining member and press the same toward the seat of said drain receptacle.

3. In a device of the character described, a hose leading from a delivery receptacle, a nozzle carried by said hose and having a circumferential flange forming a shoulder thereon, a drain receptacle having means to connect the same with a storage reservoir, adapted to

receive said nozzle and having a seat to engage said shoulder, a supporting plate secured to said drain receptacle, a retaining member having a bifurcated end portion, the arms of which are movable into and out of engagement with said flange on the opposite sides of the hose, said member being supported at one end on said supporting plate for sliding movement and rocking movement with relation thereto and having the arms of its bifurcated end tapered, and also having a slot formed therein, a shaft, a disk eccentrically mounted on said shaft and arranged in said slot, a handle connected with said shaft for actuating said disk, a part secured to said supporting plate and arranged to engage the tapered arms of said retaining member and press the same toward the seat of said drain receptacle, and means to lock said handle in a position to hold the retaining device in operative engagement with said nozzle.

4. In a device of the character described, a hose leading from a delivery receptacle, a nozzle carried by said hose and having a circumferential flange, one side of which is tapered to form a shoulder, a drain receptacle having an outlet to connect the same with a storage receptacle, and having one end open to receive said nozzle, a supporting plate rigidly secured to said drain receptacle near the open end thereof, a seat arranged within said open end of said drain receptacle to engage the shoulder on said nozzle, a bracket mounted on said supporting plate and having a semi-circular flange arranged to overhang the flange on said nozzle when the latter has been inserted in said drain receptacle, an actuating device having a part movable into and out of engagement with said flange of said nozzle, said part having an inclined surface to engage the flange of said bracket, whereby said flange will be forced toward the seat in said drain receptacle.

5. In a device of the character described, a hose leading from a delivery receptacle, a discharge nozzle connected with said hose, a drain receptacle adapted to receive said nozzle and having an outlet to connect the same with a storage reservoir, a valve to control said outlet, and means controlled by said nozzle to actuate said valve.

6. In a device of the character described, a hose leading from a delivery receptacle, a discharge nozzle connected with said hose, a drain receptacle adapted to receive said nozzle and having an outlet to connect the same with a storage receptacle, a valve to control said outlet, and an actuating device operatively connected with said valve and arranged to be engaged and operated by said nozzle after the latter has entered said drain receptacle.

7. In a device of the character described, a hose leading from a delivery receptacle, a discharge nozzle connected with said hose,

- a drain receptacle adapted to receive said nozzle and having an outlet to connect the same with a storage reservoir, a rock shaft mounted adjacent to said outlet, a valve connected with said rock shaft and movable into and out of a position to close said outlet, and a finger secured to said rock shaft and arranged within said drain receptacle in the path of said nozzle.
10. 8. In a device of the character described, a hose leading from a delivery receptacle, a discharge nozzle connected with said hose, a drain receptacle adapted to receive said nozzle and having an outlet to connect the same with a storage reservoir, a valve to control said outlet, means tending to automatically move said valve to its closed position, and an actuating device connected with said valve to move the same toward its open position,
15. 9. In a device of the character described, a hose leading from a delivery receptacle, a discharge nozzle connected with said hose, a drain receptacle adapted to receive said nozzle and having an outlet to connect the same with a storage reservoir, a valve to control said outlet, an actuating device for said valve arranged to be engaged by said nozzle after the latter has entered said drain receptacle, and means to retain said nozzle in engagement with said actuating device.
10. 10. In a liquid dispensing apparatus, a delivery receptacle, a hose leading from said delivery receptacle, a discharge nozzle connected with said hose, a drain receptacle adapted to receive said nozzle and having an outlet to connect the same with a storage reservoir, and a controlling device for said outlet comprising a part arranged to be actuated by said nozzle after the latter has entered said drain receptacle.
11. 11. In a liquid dispensing apparatus, a delivery receptacle, a hose leading from said delivery receptacle, a valve to control the passage of liquid through said hose, a discharge nozzle connected with said hose, a drain receptacle adapted to receive said nozzle and having an outlet to connect the same with a storage reservoir, and means actuated by the movement of said nozzle in said drain receptacle to open the valve which controls the passage of liquid through said hose.
12. 12. In a liquid dispensing apparatus, a delivery receptacle, a hose leading from said delivery receptacle, a valve to control the passage of liquid through said hose, a discharge nozzle connected with said hose, a drain receptacle adapted to receive said nozzle and having an outlet to connect the same with a storage reservoir, and actuating means for the valve which controls the passage of liquid through said hose, said actuating means being so arranged with relation to said drain receptacle that it will be operated when said nozzle is inserted in said drain receptacle.
13. 13. In a liquid dispensing apparatus, a delivery receptacle, a hose leading from said receptacle, a valve to control the passage of liquid through said hose, a discharge nozzle connected with said hose, a drain receptacle adapted to receive said nozzle and having an outlet to connect the same with a storage reservoir, a valve to control said outlet, and means actuated by said nozzle when the latter is inserted in said drain receptacle to open both the last mentioned valve and the valve which controls the passage of liquid through said hose.
14. 14. In a device of the character described, a hose leading from a delivery receptacle, a valve to control the passage of liquid through said hose, a discharge nozzle connected with said hose, a drain receptacle adapted to receive said nozzle and having an outlet to connect the same with a storage reservoir, a valve to control said outlet, a rock shaft, an operative connection between said rock shaft and the last mentioned valve, and an operative connection between said rock shaft and the valve in said hose line, and a finger connected with said rock shaft and arranged to be engaged by said nozzle when the latter is inserted in said drain receptacle.
15. 15. In a device of the character described, a hose leading from a delivery receptacle, a valve to control the passage of liquid through said hose, a discharge nozzle connected with said hose, a drain receptacle adapted to receive said nozzle and having an outlet to connect the same with a storage reservoir, a valve to control said outlet, a pivoted finger operatively connected with the last mentioned valve and arranged to be engaged by said nozzle when the latter is inserted in said drain receptacle, a rock arm connected with said finger, a rod connected with said rock arm, an actuating finger connected with the valve which controls the passage of liquid through said hose and arranged to be engaged and actuated by said rod.
16. 16. In a liquid dispensing apparatus, a delivery receptacle, a hose leading from said delivery receptacle, a valve to control the flow of liquid through said hose, a drain conduit leading to a storage reservoir, means for connecting said hose with said drain conduit to permit the liquid to drain from said delivery receptacle through said hose to said storage reservoir, and means controlled by said connecting means to actuate said valve.
17. 17. In a liquid dispensing apparatus, a delivery receptacle, a hose leading from said delivery receptacle, a valve to control the flow of liquid through said hose, a drain conduit leading to a storage reservoir, a device for connecting said hose with said drain conduit, comprising a nozzle on said hose, a receptacle connected with said drain conduit

- and adapted to receive said nozzle, and means for retaining said nozzle in the last mentioned receptacle, and means controlled by a movable part of said connecting device for actuating said valve.
18. In a liquid dispensing apparatus, a delivery receptacle, a hose leading from said delivery receptacle, a valve to control the flow of liquid through said hose, a discharge nozzle connected with said hose, a drain receptacle connected with a storage reservoir and adapted to receive said nozzle, and means operable only after said nozzle has been inserted in said drain receptacle to open the valve which controls the flow of liquid through said hose.
19. A liquid dispensing pump including in combination, a container for serving liquid, a hose connected with the said container, a nozzle for the hose provided with a flange, a drain line adapted to be connected with the hose, means adapted to effect the combination with the flange of the hose nozzle and drain line, and a lever operable to engage the said flange to seal the said connection together with means for interlocking the parts in the said relation.
20. A liquid dispensing pump including in combination, a container for serving liquid, a hose connected with the said container, a nozzle for the said hose, a drain line adapted to be connected with the hose, means for effecting the connection between the drain line and the hose nozzle, a lever adapted to be disposed over a portion of the said nozzle for securing the said connection, and means for locking the lever in the said relation.
21. A liquid dispensing pump including in combination, a container for serving liquid, a hose connected with the said container, a drain line adapted to be connected with the hose, means for effecting a connection between the hose nozzle and drain line, and a lever having an element adjustable relatively to and to engage a shoulder of the said nozzle upon operation of the lever for securing the nozzle and drain connection.
22. A liquid dispensing pump including in combination, a container for serving liquid, a hose connected with the said container, a drain line adapted to be connected with the hose, means comprising a gasketed housing arranged relative to an aperture in the drain line adapted for effecting a connection with an enlarged portion of the hose nozzle, and means operable for securing and sealing the said connection.
23. In a liquid dispensing apparatus comprising a delivery receptacle and a hose leading from said receptacle, a drain receptacle having an outlet to connect the same with a storage receptacle, a nozzle carried by said hose and adapted to enter said drain receptacle, said elements having cooperating parts to form a sealed connection between the same, a lever carried by one of said elements, and means connected with said lever and arranged to engage the other of said elements to press one of said cooperating parts into sealing contact with the other of said parts.
24. In a liquid dispensing apparatus comprising a delivery receptacle and a hose leading from said receptacle, a nozzle carried by said hose, a drain receptacle to receive said nozzle and having an outlet to connect the same with a storage receptacle, said nozzle and said drain receptacle having parts to seal the connection between the same, a lever mounted on said drain receptacle, and a part connected with said lever and arranged to engage said nozzle and press one of said sealing parts into engagement with the other sealing part.
25. A liquid dispensing apparatus comprising an elevated container from which liquid is served, a hose connected with said container, a discharge nozzle carried by said hose, a drain receptacle adapted to receive said nozzle, a shoulder on said nozzle adapted to contact with the inlet end of the drain receptacle, means for pressing said shoulder and the inlet end of said drain together to seal said connection, a gasket between said flange and said inlet end of the drain and means for locking the parts in sealed relation.
26. A liquid dispensing apparatus comprising an elevated container from which liquid is dispensed, a hose attached to said elevated container to drain it, a nozzle on said hose, a drain-back pipe adapted to drain back to storage liquid in the container in excess of the maximum quantity to be served at one dispensing discharge, a drain connection below said container connected with said drain back pipe and having an open end adapted to receive the discharge end of said nozzle, means for making a fluid tight joint between said nozzle and drain and means to prevent the escape of vapors from said drain back pipe through said drain when the latter is not occupied by said nozzle.

In testimony whereof, I affix my signature hereto.

EARL E. EICKMEYER.
